UNITED STATES PATENT OFFICE

167,792

RAILWAY CAR NUMBERING SIGN

Frank P. Brown, Midlothian, and Merrill G. Marshall, Homewood, Ill., assignors to Pullman-Standard Car Manufacturing Company, Chicago, Ill., a corporation of Delaware

Application August 10, 1950, Serial No. 11,704

Term of patent 14 years

(Cl. D1—12)

To all whom it may concern:

Be it known that we, Frank P. Brown and Merrill G. Marshall, citizens of the United States of America, and residents, respectively, of Midlothian, county of Cook, and State of Illinois, and Homewood, county of Cook, and State of Illinois, have invented a new, original, and ornamental Design for Railway Car Numbering Sign, of which the following is a specification, reference being had to the accompanying drawings forming part thereof.

In the drawings—

Fig. 1 is a front perspective view of the railway car numbering sign of our new design; and

Fig. 2 is a perspective view showing the rear and bottom portions of the sign.

The dominant features of the design reside in the features shown in full lines.

What is claimed is:

The ornamental design for a railway car numbering sign, substantially as shown and described.

FRANK P. BROWN.

MERRILL G. MARSHALL.
